(57) **ABSTRACT**

A medium conveying apparatus includes a housing including an accommodation portion provided with a guide portion at an end portion in a width direction, a tray accommodated in the accommodation portion so as to be pulled out, and including a placing surface for placing an ejected medium, and an engaging portion provided on a side surface of the tray, to engage the guide portion. The guide portion includes a pair of rails inclined upward and having a predetermined width. The engaging portion includes two protrusions provided so as to slide between the pair of rails and located apart from each other by a predetermined distance. By locating the two protrusions between the pair of rails, the tray is positioned at a predetermined position with respect to the housing with a front end portion of a downstream side in the medium ejecting direction located upward.

RAILS**

**CROSS-REFERENCE TO RELATED
APPLICATIONS**

This application is based upon and claims the benefit of priority of prior Japanese Patent Application No. 2020-198674, filed on Nov. 30, 2020, the entire contents of which are incorporated herein by reference.

TECHNICAL FIELD

Embodiments discussed in the present specification relate to medium conveyance.

BACKGROUND

Recently, a medium conveying apparatus, such as a scanner, conveying a medium to image the medium, and ejecting, is desired to downsize its device size when not in use. Therefore, for example, a medium conveying apparatus of tray accommodation type in which a tray to place the ejected medium is provided so as to be pulled out from an accommodation portion of a body, and the tray is accommodated in the accommodation portion when not in use, is utilized.

A sheet loading apparatus including a first tray and a second tray to increase an inclination angle by tilting up the first tray in conjunction with a drawing of the second tray, is disclosed (see Japanese Unexamined Patent Application Publication (Kokai) No. 2018-203524).

SUMMARY

According to some embodiments, a medium conveying apparatus includes a housing including an accommodation portion provided with a guide portion at an end portion in a width direction perpendicular to a medium ejecting direction, a tray accommodated in the accommodation portion so as to be pulled out, and including a placing surface for placing an ejected medium, and an engaging portion provided on a side surface of the tray, to engage the guide portion. The guide portion includes a pair of rails inclined upward and having a predetermined width. The engaging portion includes two protrusions provided so as to slide between the pair of rails and located apart from each other by a predetermined distance. By locating the two protrusions between the pair of rails, the tray is positioned at a predetermined position with respect to the housing with a front end portion of a downstream side in the medium ejecting direction located upward.

BRIEF DESCRIPTION OF DRAWINGS

FIG. 1 is a perspective view illustrating a medium conveying apparatus 100 according to an embodiment.

FIG. 2 is a perspective view illustrating the medium conveying apparatus 100 according to the embodiment.

FIG. 3 is a side view of the medium conveying apparatus 100, as viewed from the side.

FIG. 4 is a schematic diagram for illustrating a first ejection tray 105.

FIG. 5A is a schematic view for illustrating the first ejection tray 105, etc.

FIG. 5B is a schematic view for illustrating the first ejection tray 105, etc.

FIG. 6A is a schematic view for illustrating the first ejection tray 105, etc.

FIG. 6B is a schematic view for illustrating the first ejection tray 105, etc.

FIG. 7 is a diagram for illustrating a conveyance path inside the medium conveying apparatus 100.

FIG. 8 is a schematic diagram for illustrating another first ejection tray 205.

FIG. 9 is a schematic diagram for illustrating another accommodation portion 201b.

FIG. 10A is a schematic diagram for illustrating an operation of the first ejection tray 205.

FIG. 10B is a schematic diagram for illustrating the operation of the first ejection tray 205.

FIG. 11A is a schematic diagram for illustrating the operation of the first ejection tray 205.

FIG. 11B is a schematic diagram for illustrating the operation of the first ejection tray 205.

FIG. 12A is a schematic diagram for illustrating the operation of the first ejection tray 205.

FIG. 12B is a schematic diagram for illustrating the operation of the first ejection tray 205.

FIG. 13A is a schematic diagram for illustrating the operation of the first ejection tray 205.

FIG. 13B is a schematic diagram for illustrating the operation of the first ejection tray 205.

FIG. 14 is a schematic diagram for illustrating a size of a first protrusion 205f, etc.

DESCRIPTION OF EMBODIMENTS

It is to be understood that both the foregoing general description and the following detailed description are exemplary and explanatory, and are not restrictive of the invention, as claimed.

Hereinafter, a medium conveying apparatus according to an embodiment, will be described with reference to the drawings. However, it should be noted that the technical scope of the invention is not limited to these embodiments, and extends to the inventions described in the claims and their equivalents.

FIGS. 1 and 2 are perspective views illustrating a medium conveying apparatus 100 configured as an image scanner. FIG. 1 illustrates the medium conveying apparatus 100 in a state where an ejection tray 104 is accommodated. FIG. 2 illustrates the medium conveying apparatus 100 in a state where the ejection tray 104 is set.

The medium conveying apparatus 100 conveys, images, and ejects the medium being a document. A medium is a paper, a thick paper, a card, a brochure, a passport, etc. The medium conveying apparatus 100 may be a fax machine, a copying machine, a multifunctional peripheral (MFP), etc. A conveyed medium may not be a document but may be an object being printed on etc., and the medium conveying apparatus 100 may be a printer etc.

The medium conveying apparatus 100 includes a lower housing 101, an upper housing 102, a medium tray 103, and an ejection tray 104, etc. An arrow A1 in FIGS. 1 and 2 indicates a medium ejecting direction. Hereinafter, an upstream refers to an upstream in the medium ejecting direction A1, and a downstream refers to a downstream in the medium ejecting direction A1. An arrow A2 indicates a width direction perpendicular to the medium ejecting direction A1. An arrow A3 indicates a height direction perpendicular to an upper surface of the ejection tray 104.

The lower housing 101 and the upper housing 102 are an example of a housing. The upper housing 102 is located in a position covering a top surface of the medium conveying apparatus 100, and is engaged with the lower housing 101 by a hinge. The lower housing 101 and the upper housing 102 include an ejection port 101a to eject the medium. The lower housing 101 is an example of a housing, and includes an accommodation portion 101b to accommodate the ejection tray 104.

The medium tray 103 is engaged with the lower housing 101 in such a way as to be able to place a medium to be conveyed.

The ejection tray 104 is provided below the ejection port 101a, and is attached to the lower housing 101 so as to place the medium ejected from the ejection port 101a. The ejection tray 104 is formed of a resin member or a metal member, etc. The ejection tray 104 is accommodated in the accommodation portion 101b of the lower housing 101 when the medium conveying apparatus 100 is not used, and the ejection tray 104 is drawn from the lower housing 101 in the medium ejecting direction A1, to place the medium ejected from the ejection port 101a when the medium conveying apparatus 100 is used. The ejection tray 104 includes a first ejection tray 105, a second ejection tray 106, a third ejection tray 107, a stopper 108 and a cover 109.

The first ejection tray 105 is an example of a tray, is accommodated in the accommodation portion 101b of the lower housing 101 so as to be pulled out, and includes a placing surface 105a for placing the ejected medium. The first ejection tray 105 is provided so as to be pulled out from the accommodation portion 101b in the medium ejecting direction A1. The first ejection tray 105 is accommodated in the accommodation portion 101b when not in use, and the first ejection tray 105 is pulled out from the accommodation portion 101b to place the ejected medium when used.

The second ejection tray 106 is accommodated in the first ejection tray 105 so as to be pulled out, and has a placing surface 106a for placing the ejected medium. The second ejection tray 106 is provided so as to be pulled out from the first ejection tray 105 in the medium ejecting direction A1. The second ejection tray 106 is accommodated in the first ejection tray 105 when not in use, and the second ejection tray 106 is pulled out from the first ejection tray 105, to place the ejected medium, particularly large size media when used.

The third ejection tray 107 is accommodated in the second ejection tray 106 so as to be pulled out, and includes a placing surface 107a for placing the ejected medium. The third ejection tray 107 is provided so as to be pulled out from the second ejection tray 106 in the medium ejecting direction A1. The third ejection tray 107 is accommodated in the second ejection tray 106 when not in use, and the third ejection tray 107 is pulled out from the second ejection tray 106, to place the ejected medium, particularly larger size media when used.

The stopper 108 is provided foldably with respect to the third ejection tray 107, to stop a front end of the ejected medium, and regulate the front end of each medium, in a standing state.

The cover 109 is a cover for covering the first ejection tray 105, the second ejection tray 106, the third ejection tray 107 and the stopper 108 accommodated in the lower housing 101. The cover 109 covers the accommodation portion 101b along with a front end portion 105b of the downstream side of the medium ejecting direction A1 of the first ejection tray 105, and prevent dust, etc., from entering the accommodation portion 101b.

FIG. 3 is a side view of the medium conveying apparatus 100, as viewed from the side.

As illustrated in FIG. 3, the ejection tray 104 is located inclined with respect to an installation surface H where the medium conveying apparatus 100 is installed, such that the front end portion of the downstream side of the medium ejecting direction A1 is positioned upward. The first ejection tray 105, the second ejection tray 106 and the third ejection tray 107 are formed in a substantially planar shape (substantially linear when viewed from the side). The first ejection tray 105, the second ejection tray 106 and the third ejection tray 107 are located such that the inclination with respect to the installation surface H is gradually increase, in the order of the first ejection tray 105, the second ejection tray 106 and the third ejection tray 107.

FIG. 4 is a schematic diagram for illustrating the first ejection tray 105. FIG. 4 illustrates the first ejection tray 105 in a state where the first ejection tray 105 is removed from the lower housing 101, and the second ejection tray 106, the third ejection tray 107 and the stopper 108 are accommodated.

As illustrated in FIG. 4, the first ejection tray 105 includes a placing portion 105d and two engaging portions 105e. The placing portion 105d includes a placing surface 105a, to place the ejected medium on the placing surface 105a. The two engaging portions 105e are provided on two side surfaces 105c of the first ejection tray 105, i.e., on both ends in the width direction A2 perpendicular to the medium ejecting direction. The number of the engaging portion 105e may be one. In this case, the engaging portion 105e is provided only on one side surface 105c of the first ejection tray 105. Each engaging portion 105e includes a first protrusion 105f, a second protrusion 105g, a bond portion 105h and an auxiliary supporting portion 105i, etc.

The first protrusion 105f and the second protrusion 105g are located apart from each other by a predetermined distance in the medium ejecting direction A1. The first protrusion 105f and the second protrusion 105g protrude upward from the placing surface 105a of the first ejection tray 105 in the height direction A3, respectively. The first protrusion 105f and the second protrusion 105g may project downward from the lower surface of the first ejection tray 105 in the height direction A3. The first protrusion 105f and the second protrusion 105g project outward from the placing surface 105a in the width direction A2.

The first protrusion 105f and the second protrusion 105g have an oval shape. In particular, the first protrusion 105f and the second protrusion 105g have a shape of two parallel sides extending in the medium ejecting direction A1 and two semicircles. The first protrusion 105f and the second protrusion 105g may have any other shape having a curved line, such as a circular shape, an elliptical shape, an egg shape, or a rounded rectangular shape. A rounded rectangle is a rectangle with rounded corners. The first protrusion 105f, the second protrusion 105g and the bond portion 105h may have a gourd-like shape as a whole.

The bond portion 105h is provided to bond the first protrusion 105f and the second protrusion 105g. The bond portion 105h protrudes outward from the placing surface 105a, and is formed so as to be flush with the first protrusion 105f and the second protrusion 105g, in the width direction A2. On the other hand, the bond portion 105h does not protrude upward from the placing surface 105a of the first ejection tray 105, and does not protrude downward from the lower surface of the first ejection tray 105, in the height direction A3. That is, the first protrusion 105f and the second

protrusion **105g** protrude upward and/or downward from the bond portion **105h** in the height direction **A3**, respectively.

The auxiliary supporting portion **105i** is located on the upstream side of the first protrusion **105f**, the bond portion **105h** and the second protrusion **105g**. The auxiliary supporting portion **105i** protrudes outward from the placing surface **105a**, and is formed so as to be flush with the first protrusion **105f**, the bond portion **105h** and the second protrusion **105g**, in the width direction **A2**. On the other hand, the auxiliary supporting portion **105i** does not protrude upward from the placing surface **105a** of the first ejection tray **105**, and does not protrude downward from the lower surface of the first ejection tray **105**, in the height direction **A3**. That is, the first protrusion **105f** and the second protrusion **105g** protrude upward and/or downward from the auxiliary supporting portion **105i** in the height direction **A3**, respectively.

FIGS. 5A, 5B, 6A and 6B are schematic diagrams for illustrating the first ejection tray **105** and the accommodation portion **101b**. FIGS. 5A, 5B, 6A and 6B are cross-sectional views of the accommodation portion **101b** cut in a cross section parallel to the medium ejecting direction **A1** and the height direction **A3**. FIG. 5A is a cross-sectional view of the accommodation portion **101b** in which the first ejection tray **105** is accommodated. FIG. 5B is a cross-sectional view of the accommodation portion **101b** in which the first ejection tray **105** is slightly pulled out. FIG. 6A is a cross-sectional view of the accommodation portion **101b** in which the first ejection tray **105** is further pulled out from a state shown in FIG. 5B. FIG. 6B is a cross-sectional view of the accommodation portion **101b** in which the first ejection tray **105** is fully pulled out.

As illustrated in FIGS. 5A, 5B, 6A and 6B, the accommodation portion **101b** is provided with a guide portion **101c** at an end portion in the width direction **A2** perpendicular to the medium ejecting direction, in particular, inside a side surface provided at both end portions in the width direction **A2** perpendicular to the medium ejecting direction. The guide portion **101c** is located so as to face the engaging portion **105e** provided on the side surface **105c** of the first ejection tray **105**. When the number of the engaging portion **105e** provided in the first ejection tray **105** is one, the guide portion **101c** is provided only on the side surface facing the one engaging portion **105e**. The guide portion **101c** includes a pair of first rails **101d**, a pair of second rails **101e** and a pair of third rails **101f**.

The pair of first rails **101d** are provided at an upstream end portion of the guide portion **101c** in the medium ejecting direction **A1**. The pair of first rails **101d** extend substantially in parallel to the installation surface of the medium conveying apparatus **100** and have a predetermined width. The predetermined width is substantially the same size as a size of the first protrusion **105f** and the second protrusion **105g** provided in the first ejection tray **105** in the height direction **A3**.

The pair of second rails **101e** is provided on the downstream side of the first rail **101d** in the medium ejecting direction **A1**. A lower rail portion of the pair of second rails **101e** is formed to be recessed downward, and the pair of second rails **101e** has a width larger than the predetermined width of the pair of first rails **101d**.

The pair of third rails **101f** is an example of a pair of rails, and is provided on the downstream side of the second rail **101e**, in particular, on a downstream end portion of the guide portion **101c**, in the medium ejecting direction **A1**. The pair of third rails **101f** is inclined upward so that the downstream

end portion is positioned upward, and has the same width as the predetermined width of the first rail **101d**.

In this manner, since the first rail **101d** extends substantially parallel to the installation surface of the medium conveying apparatus **100** and the third rail **101f** is inclined upward, the guide portion **101c** is bent upward.

As described above, the widths of the pair of first rails **101d** and the pair of third rails **101f** are substantially the same as the sizes of the first protrusion **105f** and the second protrusion **105g** of the engaging portion **105e** in the height direction **A3**. Therefore, the engaging portion **105e** engages with the pair of first rails **101d** and the pair of third rails **101f** of the guide portion **101c**. The engaging portion **105e** is provided so as to slide between the pair of first rails **101d** and the pair of third rails **101f**.

Hereinafter, a pulling out operation of the first ejection tray **105** will be described.

As illustrated in FIG. 5A, when the first ejection tray **105** is accommodated in the accommodation portion **101b**, the second protrusion **105g** of the engaging portion **105e** of the first ejection tray **105** is located between the pair of first rails **101d** and is clamped by the pair of first rails **101d**. In this case, an upper end of the first protrusion **105f** provided on the upstream side of the second protrusion **105g** and a part of an upper surface of the auxiliary support portion **105i** provided on the downstream side of the second protrusion **105g** contact an upper surface of the guide portion **101c**. Thus, the first ejection tray **105** is positioned in a predetermined accommodation position with respect to the lower housing **101**.

As illustrated in FIG. 5B, when the first ejection tray **105** is slightly pulled out from the accommodation portion **101b**, the first protrusion **105f** and the second protrusion **105g** slide along the first rail **101d** extending substantially in parallel to the installation surface of the medium conveying apparatus **100**. Thus, the first ejection tray **105** slides in substantially parallel to the installation surface of the medium conveying apparatus **100**.

As illustrated in FIG. 6A, when the first ejection tray **105** is further pulled out from the accommodation portion **101b**, the first protrusion **105f** located on the upstream side slides along the lower rail part of the second rail **101e** formed to be recessed downward. Thus, the first ejection tray **105** is inclined such that the front end portion **105b** of the downstream side in the medium ejecting direction **A1** is positioned upward.

As illustrated in FIG. 6B, when the first ejection tray **105** is fully pulled out from the accommodation portion **101b**, the second protrusion **105g** and the first protrusion **105f** are located between the pair of third rails **101f**, and are clamped by the pair of third rails **101f**. Thus, the first ejection tray **105** is positioned at a predetermined set position with respect to the lower housing **101** with the front end portion **105b** of the downstream side in the medium ejecting direction **A1** located upward.

As described above, the first protrusion **105f** and the second protrusion **105g** have a shape of two parallel sides and two semicircles. The first protrusion **105f** and the second protrusion **105g** can change an orientation smoothly by a rounded corner, when the first ejection tray **105** is pulled out from the accommodation portion **101b**, even when the first protrusion **105f** or the second protrusion **105g** come into contact with a bent position in the guide portion **101c**. Further, since the first protrusion **105f** and the second protrusion **105g** have two parallel sides, the contact surface between the first protrusion **105f** and the second protrusion **105g**, and the rail in the guide portion **101c** is large.

Therefore, the first protrusion **105f** and the second protrusion **105g** are stably clamped by the pair of first rails **101d** or the pair of third rails **101f**.

Further, the medium conveying apparatus **100** can increase the strength of the first protrusion **105f** and the second protrusion **105g** by the bond portion **105h** provided between the first protrusion **105f** and the second protrusion **105g**. Thus, the first protrusion **105f** and the second protrusion **105g** are stably clamped by the pair of first rails **101d** or the pair of third rails **101f**, and an occurrence of a breakage of the engaging portion **105e** is suppressed.

Further, since the first protrusion **105f** and the second protrusion **105g** sliding along the guide portion **101c** are located apart from each other, the recess is provided between the first protrusion **105f** and the second protrusion **105g**. Therefore, the first ejection tray **105** can change the orientation with a margin in the accommodation portion **101b**. In particular, since the medium conveying apparatus **100** is provided with the recess with respect to the upper ends of the first protrusion **105f** and the second protrusion **105g**, the first ejection tray **105** can change the orientation upward with a margin in the accommodation portion **101b**. Since the medium conveying apparatus **100** can increase the degree of freedom of the shapes of the accommodation portion **101b** and the guide portion **101c**, the developer can easily design the accommodation portion **101b** and the guide portion **101c**, and thereby, reduce the number of man-hours for developing the medium conveying apparatus **100**.

The sizes in which the first protrusion **105f** and the second protrusion **105g** of the engaging portion **105e** protrude from the upper surface of the placing surface **105a** or the bond portion **105h** are determined based on the shape of the guide portion **101c** bent upward. When the sizes in which the first protrusion **105f** and the second protrusion **105g** protrude are too small, the bond portion **105h** may collide with the guide portion **101c** at a position where the guide portion **101c** bends, and the first ejection tray **105** may not be able to change the orientation. On the other hand, when the sizes in which the first protrusion **105f** and the second protrusion **105g** protrude are too large, the size of the guide portion **101c** needs to be large, and the size of the medium conveying apparatus **100** needs to be large. The sizes in which the first protrusion **105f** and the second protrusion **105g** protrude from the upper surface of the placing surface **105a** or the bond portion **105h** is determined such that the placing surface **105a** or the bond portion **105h** do not come into contact with the guide portion **101c** when the first ejection tray **105** is pulled out.

A distance between the center positions of the first protrusion **105f** and the second protrusion **105g** is determined based on the material (hardness) or the weight of the first ejection tray **105**, and/or the arrangement positions of the first protrusion **105f** and the second protrusion **105g**. When a distance between the center positions of the first protrusion **105f** and the second protrusion **105g** of the engaging portion **105e** is too large, the bond portion **105h** may collide with the guide portion **101c** at the position where the guide portion **101c** bends, and the first ejection tray **105** may not be able to change the orientation. On the other hand, when the distance between the center positions of the first protrusion **105f** and the second protrusion **105g** of the engaging portion **105e** is too small, the engaging portion **105e** cannot support the first ejection tray **105**, and the engaging portion **105e** may be damaged. The distance between the center positions of the first protrusion **105f** and the second protrusion **105g** is determined to a length such that the engaging portion **105e** satisfactorily supports the first ejection tray **105**.

The engaging portion **105e** may have at least the first protrusion **105f** and the second protrusion **105g**, and the bond portion **105h** and/or the auxiliary support portion **105i** may be omitted.

5 FIG. 7 is a diagram for illustrating a conveyance path inside the medium conveying apparatus **100**.

The conveyance path inside the medium conveying apparatus **100** includes the feed roller **111**, the brake roller **112**, the first conveying roller **113**, the second conveying roller **114**, the first imaging device **115a**, the second imaging device **115b**, the first ejection roller **116** and the second ejection roller **117**, etc. The number of each roller is not limited to one, and may be plural. A top surface of the lower housing **101** forms a lower guide **110a** of a conveyance path of a medium, and a bottom surface of the upper housing **102** forms an upper guide **110b** of the conveyance path of a medium.

The first imaging device **115a** includes a line sensor based on a unity-magnification optical system type contact image sensor (CIS) including an imaging element based on a complementary metal oxide semiconductor (CMOS) linearly located in a main scanning direction. Further, the first imaging device **115a** includes a lens for forming an image on the imaging element, and an analog-digital (A/D) converter for amplifying and analog-digital (A/D) converting an electric signal output from the imaging element. The first imaging device **115a** generates and outputs an input image imaging a front surface of a conveyed medium, in accordance with control from a processing circuit (not shown).

20 Similarly, the second imaging device **115b** includes a line sensor based on a unity-magnification optical system type CIS including an imaging element based on a CMOS linearly located in a main scanning direction. Further, the second imaging device **115b** includes a lens for forming an image on the imaging element, and an A/D converter for amplifying and A/D converting an electric signal output from the imaging element. The second imaging device **115b** generates and outputs an input image imaging a back surface of a conveyed medium, in accordance with control from the processing circuit.

25 Only either of the first imaging device **115a** and the second imaging device **115b** may be located in the medium conveying apparatus **100** and only one surface of a medium may be read. Further, a line sensor based on a unity-magnification optical system type CIS including an imaging element based on charge coupled devices (CCDs) may be used in place of the line sensor based on a unity-magnification optical system type CIS including an imaging element based on a CMOS. Further, a line sensor based on a reduction optical system type line sensor including an imaging element based on CMOS or CCDs.

30 The medium placed on the medium tray **103** is conveyed in the medium ejecting direction **A1** between the lower guide **110a** and the upper guide **110b** by the feed roller **111** rotating in a direction of an arrow **A11** in FIG. 7. When the medium is conveyed, the brake roller **112** rotates in a direction of an arrow **A12**. By the workings of the feed roller **111** and the brake roller **112**, when a plurality of media are placed on the medium tray **103**, only a medium in contact with the feed roller **111**, out of the media placed on the medium tray **103**, is separated. Consequently, conveyance of a medium other than the separated medium is restricted (prevention of multi-feed).

35 The medium is fed between the first conveyance roller **113** and the second conveyance roller **114** while being guided by the lower guide **110a** and the upper guide **110b**. The medium is fed between the first imaging device **115a**

and the second imaging device 115b by the first conveyance roller 113 and the second conveyance roller 114 rotating in directions of an arrow A13 and an arrow A14, respectively, and is read by the first imaging device 115a and the second imaging device 115b. The first ejection roller 116 and the second ejection roller 117 eject the medium on the ejection tray 104 by rotating in directions of arrows A15 and A16, respectively. The ejecting table 104 places the medium ejected by the first ejection roller 116 and the second ejection roller 117.

As described in detail above, in the medium conveying apparatus 100, the first protrusion 105f and the second protrusion 105g which are slidable between the third rails 101f provided in the guiding portion 101c are located in the engaging portion 105e of the first ejection tray 105 which engages with the guiding portion 101c of the lower housing 101. The first protrusion 105f and the second protrusion 105g are located apart from each other. Therefore, the recess is provided between the first protrusion 105f and the second protrusion 105g which slide along the third rails 101f, and the first ejection tray 105 can change the orientation with a margin in the accommodating portion 101b when pulled out from the accommodating portion 101b. Therefore, in the medium conveying apparatus 100, the first ejection tray 105 can be pulled out satisfactorily from the accommodation portion 101b of the lower housing 101.

Generally, an ejection tray of a medium conveying apparatus has a bent shape, and/or is located to be inclined greatly in order to enhance an alignability of a medium. In order to accommodate such an ejection tray in a housing, the medium conveying apparatus needs to increase a space of an accommodation portion, and thereby, needs to increase the device size of the medium conveying apparatus. The medium conveying apparatus 100 can change the orientation of the ejection tray 104 with a margin in the accommodation portion 101b when the ejection tray 104 is pulled out from the accommodation portion 101b. Therefore, the medium conveying apparatus 100 can achieve both improving the alignability of the medium, and accommodating the ejection tray 104 in the housing, while suppressing an increase in the device size.

FIG. 8 is a schematic diagram for illustrating a first ejection tray 205 of the medium conveying apparatus according to another embodiment. FIG. 8 illustrates the first ejection tray 205 in a state where the first ejection tray 205 is removed from the lower housing 101, and a second ejection tray, the third ejection tray and the stopper are removed from the first ejection tray 205.

The first ejection tray 205 is used in place of the first ejection tray 105 of the medium conveying apparatus 100. As illustrated in FIG. 8, the first ejection tray 205 includes a placing portion 205d and two engaging portions 205e. The placing portion 205d includes a placing surface 205a, to place the ejected medium on the placing surface 205a. The two engaging portions 205e are provided on two side surfaces 205c of the first ejection tray 205, i.e., at both ends in the width direction A2 perpendicular to the medium ejecting direction. The number of the engaging portion 205e may be one. Each engaging portion 205e has a first protrusion 205f, a second protrusion 205g and a bond portion 205h, etc.

The first protrusion 205f and the second protrusion 205g are located apart from each other by a predetermined distance in the medium ejecting direction A1. The first protrusion 205f and the second protrusion 205g protrude upward from the placing surface 205a of the first ejection tray 205 in the height direction A3. The first protrusion 205f and the

second protrusion 205g may protrude downward from the lower surface of the first ejection tray 205 in the height direction A3. The first protrusion 205f and the second protrusion 205g protrude outward from the placing surface 205a in the width direction A2. The first protrusion 205f and the second protrusion 205g have an oval shape, in particular, a circular shape.

The bond portion 205h is provided so as to bond the first protrusion 205f and the second protrusion 205g to each other. The bond portion 205h protrudes outward from the placing surface 205a, and is formed so as to be flush with the first protrusion 205f and the second protrusion 205g, in the width direction A2. On the other hand, the bond portion 205h does not protrude upward from the placing surface 205a of the first ejection tray 205, and does not protrude downward from the lower surface of the first ejection tray 205, in the height direction A3. That is, the first protrusion 205f and the second protrusion 205g protrude upward and/or downward from the bond portion 205h in the height direction A3, respectively.

FIG. 9 is a schematic diagram for illustrating an accommodation portion 201b of the medium conveying apparatus according to the present embodiment. FIG. 9 illustrates the accommodation portion 201b in a state where the first ejection tray 205 is removed.

The accommodation portion 201b is used in place of the accommodation portion 101b of the medium conveying apparatus 100. As illustrated in FIG. 9, similarly to the accommodation portion 101b of the medium conveying apparatus 100, the accommodation portion 201b is provided with a guide unit 201c at an end portion in the width direction A2 perpendicular to the medium ejecting direction. The guide portion 201c is located so as to face the engaging portion 205e provided on the side surface 205c of the first ejection tray 205. The guide portion 201c includes a pair of first rails 201d.

The pair of first rails 201d is an example of a pair of rails, and is provided from the upstream end portion to the downstream end portion of the guide portion 201c in the medium ejecting direction A1. The pair of first rails 201d includes a bent portion 201g that bends upward. The pair of first rails 201d extend substantially in parallel to an installation surface of the medium conveying apparatus on the upstream side of the bending portion 201g, and are inclined upward so that the downstream end portion is positioned upward on the downstream side of the bending portion 201g. The pair of first rails 201d has a predetermined width from the upstream end portion to the downstream end portion of the guide portion 201c in the medium ejecting direction A1. The predetermined width is substantially the same size as the size of the first protrusion 205f and the second protrusion 205g provided on the first ejection tray 205 in the height direction A3. Thus, the engaging portion 205e engages with the pair of first rails 201d of the guide portion 201c and is provided so as to slide between the pair of first rails 201d.

FIGS. 10A, 10B, 11A, 11B, 12A, 12B, 13A and 13B are schematic diagrams for illustrating an operation of the first ejection tray 205. FIGS. 10A, 10B, 11A, 11B, 12A, 12B, 13A and 13B are cross-sectional views of the accommodation portion 201b cut in a cross section parallel to the medium ejecting direction A1 and the height direction A3. FIGS. 10A, 11A, 12A and 13A are cross-sectional views of the accommodation portion 201b, as viewed from above. FIGS. 10B, 11B, 12B and 13B are a cross-sectional views of the accommodation portion 201b, as viewed from below.

FIGS. 10A and 10B are cross-sectional views of the accommodation portion 201b in which the first ejection tray

11

205 is accommodated. As illustrated in FIGS. 10A and 10B, when the first ejection tray 205 is accommodated in the accommodating portion 201b, the first protrusion 205f and the second protrusion 205g of the engaging portion 205e are located between the pair of first rails 201d, and clamped by the pair of first rails 201d.

FIGS. 11A and 11B are cross-sectional views of the accommodation portion 201b in which the first ejection tray 205 is slightly pulled out. As illustrated in FIGS. 11A and 11B, the second protrusion 205g and the first protrusion 205f slide along a portion extending approximately parallel to an installation surface of the medium conveying apparatus, in the first rails 201d until they pass through the bending portion 201g. Thus, the first ejection tray 205 slides in substantially parallel to the installation surface of the medium conveying apparatus.

FIGS. 12A and 12B are cross-sectional views of the accommodation portion 201b in which the first ejection tray 205 is further pulled out from the state showed in FIGS. 11A and 11B. FIGS. 12A and 12B illustrate a state where the second protrusion 205g located on the upstream side passes through the bending portion 201g, and the first protrusion 205f located on the downstream side does not pass through the bending portion 201g yet. In the state shown in FIGS. 12A and 12B, the first protrusion 205f slides along a portion extending substantially parallel to the installation surface of the medium conveying apparatus, in the first rail 201d, and the second protrusion 205g slides along a portion inclined upward in the first rail 201d. Thus, the first ejection tray 205 is inclined such that the front end portion 205b of the downstream side in the medium ejecting direction A1 is positioned upward.

Similar to the first protrusion 205f and the second protrusion 205g of the medium conveying apparatus 100, the first protrusion 205f and the second protrusion 205g sliding along the guide portion 201c are located apart from each other, so that a recess is provided between the first protrusion 205f and the second protrusion 205g. Therefore, the engaging portion 205e of the first ejection tray 205 does not contact the bent portion 201g of the first rail 201d, and the first ejection tray 205 can satisfactorily change the orientation. In particular, since the engaging portion 205e is provided with the recess with respect to upper ends of the first protrusion 205f and the second protrusion 205g, the first ejection tray 205 can change the orientation upward in the bending portion 201g that bends upward.

FIGS. 13A and 13B are cross-sectional views of the accommodation portion 201b in which the first ejection tray 205 is fully pulled out. As illustrated in FIGS. 13A and 13B, when the first ejection tray 205 is fully pulled out from the accommodation portion 201b, the second protrusion 205g and the first protrusion 205f are located at the inclined part in the pair of first rails 201d, and clamped by the pair of first rails 201d. Thus, the first ejection tray 205 is positioned at a predetermined set position with respect to the lower housing 101 with the front end portion 205b of the downstream side in the medium ejecting direction A1 located upward.

As described above, the first protrusion 205f and the second protrusion 205g have a circular shape. Thus, the first protrusion 205f and the second protrusion 205g can change the orientation smoothly, when the first ejection tray 205 is pulled out from the accommodation portion 201b, even when the first protrusion 205f or the second protrusion 205g come into contact with the bent position in the guide portion 201c.

Further, the medium conveying apparatus can increase the strength of the first protrusion 205f and the second protrusion 205g, by the bond portion 205h provided between the first protrusion 205f and the second protrusion 205g. Thus, the first protrusion 205f and the second protrusion 205g are

12

stably clamped by the pair of first rails 201d, and the occurrence of the breakage of the engaging portion 205e is suppressed.

The engaging portion 205e may include at least the first protrusion 205f and the second protrusion 205g, and the bond portion 205h may be omitted.

FIG. 14 is a schematic diagram for illustrating sizes of the first protrusion 205f and the second protrusion 205g. FIG. 14 is a schematic view of the first ejection tray 205 and the first rail 201d, as viewed from the side. In an example illustrated in FIG. 14, it is assumed that an upper surface of the bond portion 205h is flush with the placing surface 205a of the placing portion 205d. FIG. 14 illustrates a state where a center position between the first protrusion 205f and the second protrusion 205g in an extending direction of the first ejection tray 205 on the upper surface of the bond portion 205h contact the apex of the upper bending portion 201g. That is, in FIG. 14, when the first ejection tray 205 is viewed from the side, the center position A between the first protrusion 205f and the second protrusion 205g in the extending direction of the first ejection tray 205 on the placing surface 205a is located at the same position as the apex of the upper bending portion 201g.

As illustrated in FIG. 14, when the center position A on the placing surface 205a is located at the same position as the apex of the upper bent portion 201g, angles formed by the placing surface 205a and the lower surface of the upper first rail 201d are equal on the upstream side and the downstream side of the center position A, respectively. Therefore, when an angle at which the pair of first rails 201d bends is θ , an angle formed by the placing surface 205a and the lower surface of the upper first rail 201d on the upstream side and the downstream side of the center position A is $(\theta/2)$.

The following equation (1) is established for a triangle whose apexes are a center B of the second protrusion 205g, a contact point C between the second protrusion 205g and the upper first rail 201d, and an intersection point D at which a straight line extending from the center B in the height direction of the first ejection tray 205 and the upper first rail 201d intersect.

$$\cos(\theta/2) = (t/2)/\beta \quad (1)$$

Wherein, θ is an angle at which the pair of first rails 201d is bent. t is a height (diameter) of the first protrusion 205f and the second protrusion 205g in the height direction of the first ejection tray 205. β is a distance between the center B of the second protrusion 205g and the intersection point D at which the straight line extending from the center B in the height direction of the first ejection tray 205 and the upper first rail 201d intersect in the height direction of the first ejection tray 205.

The following equation (2) is established for a triangle whose apexes are the center position A, the intersection D, and an intersection E at which the straight line extending from the center B of the second protrusion 205g in the height direction of the first ejection tray 205 and the placing surface 205a intersect.

$$\tan(\theta/2) = \alpha/(w/2) \quad (2)$$

Wherein, α is a distance between the placing surface 205a and the intersection point D in the height direction of the first ejection tray 205. w is a distance between the center position between the first protrusion 205f and the second protrusion 205g in the extending direction of the first ejection tray 205.

13

Further, the following equation (3) is established for a size h in which the first protrusion **205f** and the second protrusion **205g** protrude from the placing surface **205a** so that the placing surface **205a** provided so as to be flush with the upper surface of the bond portion **205h** is not located above the apex of the upper bending portion **201g**.

$$h \geq \alpha - (\beta - (t/2)) \quad (3)$$

In order for the engaging portion **205e** to satisfactorily support the first ejection tray **205**, the center position between the first protrusion **205f** and the second protrusion **205g** is preferably located at the same position as the center position of the placing portion **205d** in the height direction of the first ejection tray **205**. In this case, the following equation (4) is established since the size h in which the first protrusion **205f** and the second protrusion **205g** protrude from the placing surface **205a** is not equal to or larger than $\frac{1}{2}$ of the height t of the first protrusion **205f** and the second protrusion **205g**.

$$h < (t/2) \quad (4)$$

From the above equations (1) to (4), the size h in which the first protrusion **205f** and the second protrusion **205g** protrude from the placing surface **205a** is determined such that the following equation (5) is established.

$$(t/2) + (w/2) \times \tan(\theta/2) - (t/2) / \cos(\theta/2) \leq h < (t/2) \quad (5)$$

As described above, the distance w is determined based on the material (hardness) or the weight of the first ejection tray **205**, and/or the arrangement positions of the first protrusion **205f** and the second protrusion **205g**. The distance w is preferably, for example, 8 mm or more and 20 mm or less, such that the engaging portion **205e** satisfactorily supports the first ejection tray **205**. For example, when the angle θ is 5° , the height t is 5.3 mm, and the distance w is 12 mm, the size h is set to 0.3 mm or more and less than 2.7 mm.

It is prevented that the bond portion **205h** collides with the bent portion **201g** and the first ejection tray **205** is not pulled out, by the first protrusion **205f** and the second protrusion **205g** provided such that the above equation (5) is established.

As described in detail above, in the medium conveying apparatus, the first ejection tray **205** can be pulled out satisfactorily from the accommodation portion **201b** even when the accommodation portion **201b** and the first ejection tray **205** are used.

According to embodiment, in the medium conveying apparatus, the tray can be pulled out satisfactorily from the accommodation portion of the housing.

All examples and conditional language recited herein are intended for pedagogical purposes to aid the reader in understanding the invention and the concepts contributed by the inventor to furthering the art, and are to be construed as

14

being without limitation to such specifically recited examples and conditions, nor does the organization of such examples in the specification relate to a showing of the superiority and inferiority of the invention. Although the embodiment(s) of the present inventions have been described in detail, it should be understood that the various changes, substitutions, and alterations could be made hereto without departing from the spirit and scope of the invention.

What is claimed is:

1. A medium conveying apparatus comprising:
a housing including an accommodation portion provided with a guide portion at an end portion in a width direction perpendicular to a medium ejecting direction; a tray accommodated in the accommodation portion to be pulled out, and including a placing surface for placing an ejected medium; and
an engaging portion provided on a side surface of the tray, to engage the guide portion, wherein
the guide portion includes a pair of rails inclined upward and having a predetermined width, wherein
the engaging portion includes two protrusions provided to slide between the pair of rails and located apart from each other by a predetermined distance, and a bond portion, located between the pair of rails in the width direction, to bond the two protrusions, wherein
by locating the two protrusions between the pair of rails, the tray is positioned at a predetermined position with respect to the housing with a front end portion of a downstream side in the medium ejecting direction located upward, and wherein
the two protrusions protrude upward and downward from the bond portion such that the bond portion does not come into contact with the pair of rails when the tray is pulled out.
2. The medium conveying apparatus according to claim 1, wherein the protrusions have a circular or oval shape.
3. The medium conveying apparatus according to claim 1, wherein
the guide portion is bent upward, and wherein
the protrusions protrude upward from the placing surface.
4. The medium conveying apparatus according to claim 1, wherein the pair of rails includes a bent portion that bends upward, and wherein the protrusions protrude upward from the placing surface.
5. The medium conveying apparatus according to claim 4, wherein
the protrusions have a circular shape, and wherein
a size h in which the protrusions protrude from the placing surface is defined such that a following equation is established,

$$(t/2) + (w/2) \times \tan(\theta/2) - (t/2) / \cos(\theta/2) \leq h < (t/2)$$

wherein, t is a height of the two protrusions, w is a distance between center positions of the two protrusions, θ is an angle at which the pair of rails is bent.

6. The medium conveying apparatus according to claim 1, wherein the bond portion protrudes outward from side surface of the tray is flushed with the two protrusions.
